CLAIM

The ornamental design for a light fixture, as shown and described.

DESCRIPTION

FIG. 1 is a bottom perspective view of a light fixture showing my new, original, and ornamental design, which includes a central portion surrounded by a perimeter portion and recessed with respect to the perimeter portion; FIG. 2 is a top perspective view thereof;

FIG. 3 is a right side elevation view thereof;

FIG. 4 is a left side elevation view thereof;

FIG. 5 is a front elevation view thereof;

FIG. 6 is a back elevation view thereof;

FIG. 7 is a top plan view thereof; and,

FIG. 8 is a bottom plan view thereof.

The broken line disclosure represents portions of the fixture which form no part of the claimed design.
